Charles H. Welling,
By Attorney J. B. Woodruff

UNITED STATES PATENT OFFICE.

CHARLES H. WELLING, OF NEW YORK, N. Y.

DESIGN FOR A TURN-OVER COLLAR.

Specification forming part of Design No. 1,848, dated November 10, 1863.

To all whom it may concern:

Be it known that I, CHARLES H. WELLING, of the city, county, and State of New York, have invented or produced a new and original Design for a Metallic Composition Collar for Gentlemen, called "The Half Turn-Over Collar," and the following is a full and exact description of the same, reference being had to the accompanying drawings, making a part of this specification.

Figure 1 shows the shape of the pattern as cut for my design. Fig. 2 is a view of the same pattern, the front corners turned over as designed to be worn.

My improvement consists in the form or configuration of the collar, so that turn-over collars can be made of metal, and neckties or cravats can be put on and adjusted with no more inconvenience than when they are made of linen.

To enable others skilled in the art to make and use my improved collar, I will describe it in detail, referring to the drawings and the letters thereon.

I make my improved collar with the central portion, A, straight, the two edges being parallel with each other about one-half the entire length, the ends B B tapering toward the end from the under edge to about five-eighths of the width of the central or parallel part, the ends being finished in a semicircular form, having in one end a round hole, a, and in the other a hole, b, of similar size, with a slit, c, of smaller size, which admits a button or stud to clasp the two ends together. In the center or back part of the collar, near the lower edge, I have a similar hole and slit, D, in which to insert a stud to secure it to the shirt. On each side, about one-half the distance between the

ends and the center, I make oblong holes e e, in which a common pin may be inserted into the cloth or binding of the shirt to make all secure. The portion at each end of the collar to be turned over is cut angular and wider than any other part, as seen in Fig. 1. From the points i i on the upper edge, at about one-fourth of the distance from each end where the collar begins to widen, I commence to turn over, and the rounded corners o o are brought full down to or a little below the under edge of the collar, thus giving it the appearance of a well-fitted turn-over collar, while at the same time there is no difficulty experienced in putting it on or adjusting a cravat or necktie. In my metallic collars I put in a stiffening, f f, of flat wire under the part rolled over, to keep it in the proper curve, so that in the washing and cleansing or otherwise handling they will not become indented or lose their shape. The mode of securing the collars to the shirt is by having eyelet holes back and in the ends, with a slit somewhat narrower than the eyelet-hole to receive a stud or button, also a slit or oblong opening on each side in which to insert a common pin.

What I claim as a design, and desire to secure by Letters Patent, is—

The form and peculiar shape of the upper edge of the collar, whether made of metal or other material, so as to be turned over in the manner herein described, for the purposes herein specified.

Signed in New York this 12th day of October, A. D. 1863.

CHAS. H. WELLING.
